STOVE STRUCTURE

James L. Breese, Santa Fe, N. Mex., assignor to
 Oil Devices, Santa Fe, N. Mex., a limited partnership of Illinois

Application May 10, 1943, Serial No. 486,303

6 Claims. (Cl. 126—93)

This invention relates to improvements in burners and particularly for burners such as hydro-carbon burners. One object of the invention is to provide an improvement in a burner of maximum simplicity and easy assembly and disassembly which may be used for example as a tent stove burner for camping or Army use.

Another object is to provide an improved means for supplying tertiary air to such a burner and for spreading the flame.

Another object is to provide means for applying a pot type burner to a small demountable stove or heater.

Other objects will appear from time to time throughout the specification and claims.

The invention is illustrated more or less diagrammatically in the accompanying drawings, wherein

Figure 1 is a vertical axial section;

Figure 2 is a view looking in the direction of the arrows 2—2 of Figure 1;

Figure 3 is a section along the line 3—3 of Figure 1;

Figure 4 is a section along the line 4—4 of Figure 1.

Like parts are indicated by like characters throughout the specification and drawings.

Referring to the drawings, 1 generally indicates a lower member of a demountable burner. It is shown as having a closed bottom 2, side door opening 3, and an upper edge 4. Resting upon the upper edge 4 is an intermediate supporting ring generally indicated as 5. The ring is shown as having a cylindrical portion 6, fitting within and conforming closely to the upper edge of the member 1. Extending outwardly from the top of the cylindrical portion 6 is a circumferential flange 7, which rests directly upon the upper edge of the member 4. It is not important that the fit be too snug as any air which passes through the joint merely increases the supply of air in the space within the member 1.

Extending upwardly and outwardly from the flange 7 is the side wall 8 which is more or less outwardly flared and which serves to center and seat the upper edge of the upper stove member 9. The stove member is shown as somewhat upwardly tapered and having a top 10, provided with a gas aperture 11, normally closed by the removable closure 12 with the handle 13.

14 indicates an upwardly extending tapered sleeve adapted to receive any suitable stove pipe connection 15. The member 5 has an inner downwardly cylindrical portion 16 terminating in an inwardly extending ledge 17. Centered

within the sleeve 16 and resting on the ledge 17 is a cylindrical member 18 which forms part of the below described pot assembly. It may be provided with one or more locking lugs 19 provided with locking notches 19a adapted to engage enlarged portions 20 of the supporting ledge 17, as shown for example in Figures 2 and 3. Thus the pot assembly may be quickly and easily secured to or removed from the intermediate 10 supporting ring 5 of the stove. Extending inwardly from the top of the cylinder 18 is a flange 21 herein shown as having a plurality of tertiary air inlet apertures 22 extending circumferentially thereabout. Resting upon the flange 21 is the 15 outwardly turned upper edge flange 24 of the pot 23.

The pot is provided with a closed bottom 25. Its wall has therein a plurality of primary air inlet apertures 26 located at various levels. Adjacent the upper edge of the pot, are secondary air inlet apertures 27 which are preferably larger than the apertures 26 and are herein shown in a single row adjacent the open end of the pot. The pot may be held in position on the flange 21 by means of a plurality of locking screws 28 which pass through the outer edge of the flame ring 29 and penetrate the flange 21. Thus the flange, the pot and the flame ring may be unitarily secured together and may be applied to or removed 25 from the stove unitarily with the cylindrical supporting sleeve 16.

The flame ring 29 is provided with a central aperture 30. Extending up through the central aperture 30 is the air tube 31 which is secured 35 at its bottom as at 32 in an appropriate aperture in the bottom 25 of the pot. Air can thus flow upwardly through the tube 31. The tube is provided at its upper end with an outwardly extending flange 33 upon which is mounted, as by rivets or pins 34, a deflecting hood 35 with a downwardly extending circumferential flange 36. Between the flange 36 and the outer edge of the flange 33, there is defined an air outlet passage 37 through which tertiary air is downwardly directed toward the mixture, escaping upwardly through the central aperture 30 of the flame ring 29. Any suitable fuel is supplied to the lower portion of the pot along the fuel pipe 38. It will be understood that any suitable means may be 40 employed for maintaining a proper supply of fuel at a proper rate of flow. Any suitable controllable valve means not herein shown, may be employed for the rate of flow from pilot rate to high fire.

55 40 indicates a pilot ring mounted on suitable

supports 41 and provided with a central aperture 42 aligned with the central aperture 30 of the flame ring and of sufficient size to give ample clearance about the air tube 31.

In the normal use of the device, the liquid fuel which flows through the pipe 38 is vaporized on the bottom of the pot by the heat of combustion taking place in the air about the pot. When the flow of fuel along the pipe 38 is turned down to a minimum or pilot flow, the lower row of primary air inlet apertures 26 below the ring 40, provides the primary air for the vaporized fuel. The mixture of vaporized air and primary air passes upwardly through the primary aperture 42 and is converted into a completely combustible mixture by the air passing inwardly through the primary air inlet apertures 26 above the pilot baffle 40. At this stage of combustion, they therefore serve as secondary air supply means for the relatively small amount of fuel vaporized at the pilot stage.

When the rate of flow is increased to high fire stage, the level of combustion rises. At the high fire stage, all of the air inlet apertures 26 serve as primary air inlet apertures and the mixture of primary air and vaporized fuel receives its supply of secondary air through the secondary air inlets 27. This mixture then burns at or above the level of the flame ring 29. In order to provide complete combustion and to form and distribute the flame in the upper chamber 9, two inlets for tertiary air are provided, namely, the row of circumferential air inlets 22 in the flange 21 and the downwardly deflecting hood 35, 36. In practice at the high fire stage, a hot flame largely fills the housing 9 and there is a minimum of carbon deposit or soot.

I claim:

1. In a demountable stove and pot type burner therefor, a lower stove section, defining an air inlet space, and having a circumferential side wall with an air inlet aperture therein and an open top, an intermediate, inwardly extending partition ring removably mounted upon the upper edge of said lower stove section, having a central aperture, an upper stove section removably mounted upon said partition ring, having a circumferential wall and a closed top defining a combustion space, an air directing sleeve mounted upon and upwardly extending from said partition ring, and a burner pot supported on said sleeve and inwardly spaced therefrom, a transversely extending partition connecting the sleeve and the pot, the space between said sleeve and pot being in communication with the air space within the lower section, the wall of said pot being provided with a plurality of primary air inlet apertures located at various levels, and having a plurality of secondary air inlet apertures located adjacent the upper edge of the pot, all said apertures being in communication with the space within the lower section below the lower end of said sleeve.

2. In a demountable stove and pot type burner therefor, a lower stove section, defining an air inlet space, and having a circumferential side wall with an air inlet aperture therein and an open top, an intermediate, inwardly extending partition ring removably mounted upon the upper edge of said lower stove section, said partition ring having a central aperture, an upper stove section removably mounted upon said partition ring, the upper stove section having a circumferential wall and a closed top defining a combustion space, an air directing sleeve mounted

upon and upwardly extending from said partition ring, and a burner pot supported on said sleeve and inwardly spaced therefrom, a transversely extending partition connecting said sleeve and

5 pot, the space between said sleeve and pot being in communication with the air space within the lower section, said transversely extending partition being located adjacent the top of the pot and being provided with a plurality of air inlet apertures.

3. In a demountable stove and pot type burner therefor, a lower stove section, defining an air inlet space, and having a circumferential side wall with an air inlet aperture therein and an open 15 top, an intermediate, inwardly extending partition ring removably mounted upon the upper edge of said lower stove section, said partition ring having a central aperture, an upper stove section removably mounted upon said partition ring, the upper stove section having a circumferential wall and a closed top defining a combustion space, an air directing sleeve mounted upon and upwardly extending from said partition ring, and a burner pot supported on said sleeve and 20 inwardly spaced therefrom, a transversely extending partition connecting said sleeve and pot, the space between said sleeve and pot being in communication with the air space within the lower section, the wall of the pot being provided with a plurality of primary and secondary air inlet apertures, and means for delivering tertiary air directly into the combustion space.

4. In a demountable stove and pot type burner therefor, a lower stove section, defining an air inlet space, and having a circumferential side wall with an air inlet aperture therein and an open top, an intermediate, inwardly extending partition ring removably mounted upon the upper edge of said lower stove section, said partition ring having a central aperture, an upper stove section removably mounted upon said partition ring, the upper stove section having a circumferential wall and a closed top defining a combustion space, an air directing sleeve mounted upon and upwardly extending from said partition ring, and a burner pot supported on said sleeve and inwardly spaced therefrom, a transversely extending partition connecting said sleeve and pot, the space between said sleeve and pot being in communication with the air space within the lower section, the wall of the pot being provided with a plurality of primary and secondary air inlet apertures, and means for delivering tertiary air directly into the combustion space including an air duct extending upwardly through the pot and in communication with the space below the bottom of the pot, said air duct terminating at a level above the level of admission of the secondary air.

5. In a demountable stove and pot type burner therefor, a lower stove section, defining an air inlet space, and having a circumferential side wall with an air inlet aperture therein and an open top, an intermediate, inwardly extending partition ring removably mounted upon the upper edge of said lower stove section, said partition ring having a central aperture, an upper stove section removably mounted upon said partition ring, the upper stove section having a circumferential wall and a closed top defining a combustion space, an air directing sleeve mounted upon and upwardly extending from said partition ring, a burner pot supported on said sleeve and inwardly spaced therefrom, a transversely extending partition connecting said sleeve and pot, the space between said sleeve and pot being

in communication with the air space within the lower section, the wall of the pot being provided with a plurality of primary and secondary air inlet apertures, means for delivering tertiary air directly into the combustion space including an air duct extending upwardly through the pot and in communication with the space below the bottom of the pot, said air duct terminating at a level above the level of admission of the secondary air, and a hood mounted on the upper end of said duct and adapted to deliver tertiary air therefrom downwardly toward the mixture passing upwardly through the top of the pot.

6. In a demountable stove and pot type burner therefor, a lower stove section, defining an air inlet space, and having a circumferential side wall with an air inlet aperture therein and an open top, an intermediate, inwardly extending partition ring removably mounted upon the upper edge of said lower stove section, said partition ring having a central aperture, an upper stove section removably mounted upon said partition ring, having a circumferential wall and a closed

5 top defining a combustion space, an air directing sleeve mounted upon and upwardly extending from said partition ring, a burner pot supported on said sleeve and inwardly spaced therefrom, a transversely extending partition connecting the sleeve and the pot, the space between said sleeve and pot being in communication with the air space within the lower section, the wall of said pot having therein a plurality of primary air inlet apertures located at various levels, and having a plurality of secondary air inlet apertures located adjacent the upper edge of the pot, all said apertures being in communication with the space within the lower section below the lower end of 10 said sleeve and a centrally apertured flame ring partially closing the top of the pot, said ring having an outwardly extending portion secured to said transversely extending partition, said pot having an outwardly extending flange at its upper edge confined between the outwardly extending portion of said flame ring and said partition.

JAMES L. BRESEE.
